US00D680265S

(12) **United States Design Patent**
DeMarco et al.

(10) **Patent No.:** **US D680,265 S**
(45) **Date of Patent:** **** Apr. 16, 2013**

(54) **COSMETIC APPLICATOR TIP**

(75) Inventors: **Anthony DeMarco**, Mahwah, NJ (US); **Christopher Tarling**, New York, NY (US); **Timothy Thorpe**, Santa Monica, CA (US); **Janet Pardo**, New York, NY (US); **Gary Montalbano**, Matawan, NJ (US)

(73) Assignee: **HCT Packaging, Inc.**, Bridgewater, NJ (US)

(**) Term: **14 Years**

(21) Appl. No.: **29/429,587**

(22) Filed: **Aug. 14, 2012**

(51) LOC (9) Cl. **28-02**

(52) U.S. Cl.

USPC **D28/7**

(58) Field of Classification Search **D28/7, D28/8, 20-22, 30-31, 76, 85, 99; 132/108, 132/202, 208, 317.32; 401/202-207, 261-267; D4/132-135; D24/119; D9/448**

(57) **CLAIM**

The ornamental design for a cosmetic applicator tip, as shown and described.

DESCRIPTION

FIG. 1 is a perspective view of a cosmetic applicator tip; FIG. 2 is a top plan view of the cosmetic applicator tip of FIG. 1;

FIG. 3 is a front elevation view of the cosmetic applicator tip of FIG. 1;

FIG. 4 is a right-side elevation view of the cosmetic applicator tip of FIG. 1, the left-side elevation view being a mirror image of the right-side;

FIG. 5 is a bottom plan view of the cosmetic applicator tip of FIG. 1; and,

FIG. 6 is a back elevation view of the cosmetic applicator tip of FIG. 1.

The broken lines are directed to unclaimed portions and form no part of the claimed design.

1 Claim, 4 Drawing Sheets
